D. J. McCARTHY

METHOD AND MEANS FOR LOCATING LAMPS

Filed April 28, 1921

UNITED STATES PATENT OFFICE.

DANIEL J. McCARTHY, OF ELGIN, ILLINOIS, ASSIGNOR TO CHICAGO RAILWAY SIGNAL AND SUPPLY COMPANY, A CORPORATION OF ILLINOIS.

METHOD AND MEANS FOR LOCATING LAMPS.

Application filed April 28, 1921. Serial No. 465,143.

To all whom it may concern:

Be it known that I, DANIEL J. McCARTHY, a citizen of the United States, residing at Elgin, in the county of Kane and State of

5 Illinois, have invented certain new and useful Improvements in Methods and Means for Locating Lamps, of which the following is a specification.

This invention relates to methods and 10 means for locating lamps.

It will be explained as applied to a double lens signal lamp such as may be used in railway work.

In many fields, such for example as railway signalling, electric signal lamps often 15 must be located in relatively inaccessible positions such as the tops of poles, switches, signal towers, etc. The lamps burn out and otherwise become defective and must be replaced.

Not only is it important that the original lamp be properly positioned to give the desired results but replacements must give the same results. However the lamps and their 20 filaments vary in manufacture so that it is impossible to obtain uniform results by merely substituting new lamps for old ones.

The position of the original lamp may often be accurately fixed by ordinary shop 25 and laboratory photometric methods, but in the field such methods can not be followed and the apparatus necessitated thereby can not be used.

One of the objects of this invention is to 30 provide an improved method of properly locating lamps.

Another object is to provide a method and means which readily lend themselves to field use.

40 Other objects and advantages will herein-after appear.

An embodiment of apparatus whereby the improved method may be practiced is shown in the accompanying drawing.

45 The adjustable lamp support disclosed herein is claimed in my copending application Serial No. 529,484, filed January 16, 1922.

50 The device for determining the position of the lamp is claimed in my copending appli-

cation Serial No. 429,433, filed January 16, 1922.

The views in the drawings are as follows:

Fig. 1 is an elevation of a rear view of a 55 light unit showing the focus finder in place thereon.

Fig. 2 is a vertical section taken on line 2—2 of Fig. 1.

Fig. 3 is a view similar to Fig. 2, showing 60 a fragment thereof.

Fig. 4 is an enlarged sectional view of a part of the lamp adjusting support, taken on line 4—4 of Fig. 2.

Fig. 5 is a similar view to Fig. 4 taken on 65 line 5—5 of Fig. 2.

Fig. 6 is a section of part of the focus finder taken on line 6—6 of Fig. 2.

Fig. 7 shows a view in side elevation of the conventional filament of an electric lamp. 70

Fig. 8 is a diagram of the focus finder with the lamp displaced, on the focal axis and forward of the focal point.

In all the views the same reference characters are employed to indicate similar parts. 75

To obtain the highest efficiency in the projection of light by lenses, reflectors, or the like, it is quite essential that the source of light, such as the filament of an electric lamp, be placed at the exact focal point of 80 the projector; when this has been achieved the light may be made, by use of a proper arrangement of lenses, to produce a beam of light in which the rays are in parallel lines, thus projecting a more intense and far 85 reaching beam of light. By moving the lamp along the focal axis of the light projector towards the projector the rays may be made to outwardly diverge or flare while if the lamp be moved out of the focal point 90 in the opposite direction the rays of light may thus be made to converge.

In railway signal systems, in different situations, the signal lamp units are required to project beams of light in which the rays 95 are parallel; in other locations the rays of light must be diverging so as to extend over a relatively large light field at the objective point, and in others the light beam must be more concentrated at the point of applica- 100

tion. For uniformity of apparatus and economy of equipment, it is highly desirable that a single structure be made capable, by proper adjustment, to meet the various requirements of use.

It is furthermore necessary to be able to ascertain and to note the extent to which the field of illumination is extended or contracted, that is, the measure in degrees of digression from a beam of parallel rays. The instrument herein disclosed and the method of its operation is intended more particularly for readily establishing the filament of a new electric lamp in a lamp unit, in precisely the same location of the filament of the lamp initially installed in the unit, whereby it will produce the same results as the latter, although it may vary in some of its structural features or other characteristics from the original lamp.

The drawings show portions of a more or less conventional signal lamp unit in which 10 is a part of the unit casing providing a ring 11 for a lens 12, and a ring 13 for a lens 14. In this doublet arrangement or lenses, when the filament 15 of the electric lamp is located at the precise focal point, as shown in Fig. 2, the rays of light projected therefrom will form a beam in which the rays will extend in parallel lines. If the light point 15 be brought nearer to the smaller lens, the light beam will be more or less fan shape and if it be moved in the opposite direction, the beam of light will be concentrated.

A means for moving the lamp and securing it in its desired position is accomplished by the following instrumentality:—

A bracket 17 carries lamp sockets 18 and 19, the lamp 16 is shown inserted in the latter, and is the active lamp of the unit. The bracket is carried by or is part of a tube or sleeve 20, which is threaded at one end, as at 21.

A rotatable shaft 22 carries at one end an eccentric 23 to which it is fixed thru the annular sleeve 23'; at its other end it is fixed to an eccentric 25 by a pin 26. These eccentrics form journals upon which the shaft is rotatably supported and while they are shown to be somewhat different in diametric dimensions, the throw or eccentricity of the two eccentrics is the same so that, upon rotation, the shaft 22 will be moved in parallel lines around the axis of its movement. The shaft and sleeve 23' are provided with a screw driver slot 27 for convenience of rotation or they may be rotated by a wrench engaging the annular sleeve 23'. The eccentric 25 is rotatable freely in a socket 28 which is a fixed part of the frame 10. To retain the eccentric 25 in the socket it is provided with a groove 29 into which a screw 30 projects from the socket 28.

The eccentric 23 is rotatable in a ring 31

which is part of a rearwardly extending arm 32, which also carries the eccentric bearing or socket 28. Arm 32 is bifurcated at its inner end providing supplementary arms 33 and 34 fixed to the frame 10 by screws 35.

A tube or sleeve 36 overlies a large portion of shaft 22 and is freely rotatable with respect thereto. It is provided with an axially parallel slot 37 into which a screw 38, from the bracket sleeve 20, projects to permit the latter sleeve to be axially moved thereon and to cause said sleeves 20 and 36 to be rotated as one.

A nut 39, rotatable on the sleeve 36, is prevented from being axially moved thereon by a screw 40, which extends therefrom into an annular groove 41 in the sleeve. The sleeve 36 is normally held in fixed position with respect to the frame 10 by a set screw 41' which passes thru a hub 42 of sleeve 23'. The screw 41' is held in clamping position by a nut 43. The sleeve 23' is fixed by a set screw 44 which passes thru the hub 45 of ring 31, which is a part of the frame 10. A check nut 46 securely holds the clamping set screw 44 in clamping position.

From the above description it will be manifest that the lamp 16 may be moved to any desired point in a plane transverse to the focal axis of the lens combination by rotation of the shaft 22 and its connected eccentrics and that it may also be moved along the focal axis by rotation of the nut 39 and fixed in its adjusted positions by the set screws 41' and 44.

At the time when the light signal unit is assembled, a lamp 16 is placed in the socket 19 and its filament energized. The filament is then placed approximately at the focal point of the lens combination.

The beam of light from the outer lens is now measured photometrically. The lamp and filament are then movably adjusted and readings taken from the photometer until the exact focal point has been thus ascertained, whereupon the shiftable parts of the lamp adjusting device are locked in fixed positions by the set screws. Of course, if it is desired to have the signal unit project a flaring beam of determined degree the lamp and filament are adjusted accordingly. Any suitable method and apparatus for photometric calibration and measurement may be used.

After the lamp signal unit has been installed in service, it sometimes happens that a new electric lamp must replace the original and the filament of the new lamp must occupy the same position as that of the original electric lamp.

The original shop method of finding the desired location or focal point, cannot be pursued for placing a new lamp because the unit is supported on a pole or other inaccessible location and for this reason it is im-

practicable or impossible to follow the original procedure outlined above.

I have therefore provided a focus finder and a method for reestablishing the initial 5 relation with a substitute electric lamp and its associated lenses.

The instrument consists of a small closed casing 50 having an observation aperture 51. A portion of its edge wall is in-curved, as 10 at 52, the curved portion extending something more than 90 degrees and having portions of its wall inclined at 45 degrees from the perpendicular, as at 53 and 54. A small lens 55 is secured in an opening in the 15 curved portion 52 of the housing wall vertically above the filament 15 and another similar lens 56 is located in an opening in said curved wall just 90 degrees removed. A light reflector 57 is secured to the wall 20 54, inclined just 45 degrees from the focal axis of the lens 55. A similar mirror or reflector 58 is fixed in the same manner to the inclined wall 53 and inclined 45 degrees from the focal axis of the lens 56 so that 25 the beams of light reflected from the mirrors or reflectors 57 and 58 will be in planes precisely 90 degrees in angular relation to each other.

A plate of ground glass 59 is placed in the 30 path of the beam 60 of reflected light and located at right angles thereto, upon which to receive the image 15^a of the lamp filament 15.

A plate of ground glass 61 is placed in the 35 path of the beam 62 of reflected light from the lens 56 and located at right angles thereto, upon which to receive the image 15^b of the lamp filament 15.

A reflector 62' is placed over the plate 40 61 and inclined substantially 45 degrees so that an observer looking thru the aperture 51 will see the two reflected images 15^a and 15^b as they appear in Fig. 1, when the lamp filament 15 is in the position occupied by 45 the original lamp which is the focal point of the lens combination.

The plates 59 and 61 each have a longitudinally extending central line 63 which blend into the line 63^a as they appear to the 50 observer in Fig. 1. They each have a transversely extending line 64 and 65, respectively. When the images 15^a and 15^b are symmetrical with respect to the associated transverse lines and with respect to the single vertical line 63^a, as shown, the former 55 relations of the light point of the lamp and lenses have been reestablished and the signal unit will operate with the new lamp in the manner as before its original lamp became 60 defective.

Should adjustment be required to produce divergence of light rays of 5 degrees, 10 degrees or 15 degrees as exigencies of the case may require, at the field of illumination, means are provided for accurately as-

certaining the degree to which the light beam will be laterally extended.

Fig. 8 shows the filament 15 moved toward the lens on the focal axis so that the angle of the light beam 60 is raised above 70 the line 65, in a manner clearly apparent, in which event the image 15^a will be raised to the short lines 5, 10 or 15, according to the degree of beam expansion, on the plate 59, shown more clearly in Fig. 2—indicative 75 of the respective degrees to which the light beam has been spread by the forward movement of the lamp 16.

Since, in the above example, the lamp is moved along the focal axis of the lens, there 80 will be no disturbance of the light projected thru lens 56; therefore the image 15^b will remain on cross line 64.

To adjust the instrument 50 to a lamp signal unit in which the electric lamp has been 85 located, in the manner heretofore described, so that it may be removed and subsequently replaced with accuracy, the casing 50 has projecting forwardly therefrom a tapered stem 66, having a transverse notch 67 in its smaller free end. At approximately the proper position in the frame 10 a socket 68 is made, which is considerably larger than stem 66. A sleeve 69, the bore of which is tapered to neatly fit the stem 66, has one or 90 more grooves 70 and a transverse pin 71 which the transverse notch 67 of the stem engages to prevent rotation of the stem and attached instrument.

When the filament 15 has been properly 100 located by adjustment of the instrument the latter is fixed and temporarily held, with the stem 66 and sleeve 69 in the socket 68, and with the image 15^a and 15^b, as shown in Fig. 1. Then metal such as Babbitt metal, zinc or lead, 72, is poured into the socket and around the sleeve 69 to hold the latter in place in the socket. The instrument will now visually show the true focal point of the lens, and may be removed and reinserted 105 for subsequent use.

The instrument may advantageously be used in connection with a parabolic reflector, or other reflector.

While I have herein shown and described 115 a single embodiment of the invention for the purpose of a clear disclosure, it is manifest that many changes may be made in the configuration and disposition of the parts within the scope of the appended claims.

Having described my invention what I claim as new and desire to secure by Letters Patent, is:—

1. The method of locating a lamp filament at an objective point which consists in illuminating the filament; projecting two beams of light therefrom at substantially right angles to each other; reflecting both of the beams towards each other; providing a receptive surface, one for each beam upon 125 130

which the respective beams impinge and adjusting the lamp for position until said beams of light appear at predetermined objective points on two adjacent surfaces.

5. 2. The method of locating a lamp filament at an objective point which consists in arranging two lenses, the axes of which are angularly displaced 90 degrees from each other; placing a luminous lamp filament

10 near where the axes cross; projecting a beam

of light from the filament thru each lens to a reflector one for each beam; reflecting both of the beams toward each other to two receptive surfaces and adjusting the lamp for position until the beams appear near the two 15 points previously established on said receptive surfaces.

In testimony whereof I hereunto subscribed my name.

DANIEL J. McCARTHY.
